CLAIM

We claim the ornamental design for a flashlight, as shown and described.

DESCRIPTION

FIG. 1 is a top perspective view of a flashlight;

FIG. 2 is a bottom perspective view thereof;

FIG. 3 is a top view thereof;

FIG. 4 is a right side view thereof, the left side view (omitted) being a mirror image thereof;

FIG. 5 is an end elevational view thereof;

FIG. 6 is an opposite end elevational view thereof; and,

FIG. 7 is a bottom view thereof.
